BUILDER'S TOOL OR IMPLEMENT

Frank Seninger, Frank A. Goeke, Albert A. A. Nash, and Louis A. Dell'Orco, St. Louis, Mo.

Application September 22, 1932, Serial No. 634,332

5 Claims. (Cl. 304—40)

This invention relates to builders' tools or implements. In the construction of certain classes of buildings, it is customary after laying and leveling up the lower or ground floor, to then prepare for the second floor by erecting series of shore posts all cut uniformly to the required length, these posts being evenly spaced in rows upon the lower floor and being tied together by strips lightly nailed thereto. The floor beams of the next floor are then nailed to the sides of the tops of these shore posts. This temporary structure is further strengthened by means of props or underpinning braced from the lower floor up under the lower edges of the beams, after which the floor material is laid over the top edges of the beams. In the case of concrete floors, sheeting of metal lath is first nailed to the beams and the concrete spread thereupon. After the second floor is thus laid, all the said shore posts and underpinning are knocked down and again erected in the same way upon the completed second floor, preparatory to the laying of the third floor in the same way. This nailing up and knocking down of the timbers entails a very considerable expenditure of time and labor, as well as waste of material.

It is the chief object of the present invention, therefore, to provide a removable bracket or beam supporting stirrup, which may be readily mounted atop a shore post in the situation described, and to which the beam may be releasably locked, thus eliminating the use of nails.

It is a further object to provide a device of the kind referred to, comprising two arms adapted to engage at their upper ends the top end of a shore post at opposite sides thereof, and a stirrup pivotally supported between the pendent lower ends of the arms at the intermediate face of the post upon which stirrup the beam may be supported, and releasable means for locking the assembly to the post and to the beam.

With these and such other and further objects and advantages in view as may be developed in the following specification, attention is now directed to the accompanying drawings as exemplifying several practical embodiments of our invention, and wherein:

Figure 1 is a side elevation of our invention as mounted atop a shore post and supporting a floor beam beneath a course of sheeting, the post being shown partly broken away and the beam and sheeting being shown in section.

Figure 2 is a frontal elevation of the assembly of Figure 1.

Figure 3 is an enlarged longitudinal sectional view through the device alone, constituting the subject of the invention.

Figure 4 is a frontal elevation of the device as represented in Figure 3.

Figure 5 is a side elevation of a modified form

of the bracket, as attached atop a shore post and supporting a beam, the post being represented as broken away at the lower end, and the beam being shown in section.

Figure 6 is a frontal elevation of the assembly of Figure 5.

Figure 7 is a side elevation of still another modification as mounted upon a shore post and supporting a beam, the post being represented as broken away at the lower end and the beam being shown in section.

Figure 8 is a frontal elevation of the assembly of Figure 7.

As represented in Figures 1 to 4 inclusive, the invention comprises a pair of hanger or stirrup arms 1 adapted for positioning at opposite sides of a four-sided shore post 2, in an angularly pendent manner, the upper ends of the arms being formed with inwardly turned top flanges or lugs 3 adapted to flatly overlie the top 4 of 20 the post, and similar side flanges or lugs 5 adapted to overlie two opposite sides 6 of the post, the two flanges being connected together and extended perpendicularly to each other, as shown. As stated, these arms are arranged to depend angularly across two opposite sides of the post, and so that their lower ends may protrude somewhat beyond the intermediate third side 7 of the post. The protruding portions of these lower ends are likewise provided with inwardly turned bottom and side flanges or lugs 8 and 9 respectively and which are connected and extended perpendicularly to each other, the inner margins 10 of the bottom flanges or lugs 8 being adapted to overlie and bear against the corners of the post defining the side 7 thereof. Thus, when the device is properly mounted upon the post 2, the side flanges 9 are held in an outstanding relation to the side 7 of the post, thereby forming a sort of pocket, socket or stirrup 11 40 for the reception of a separate or individual back plate or beam rest 12. A beam supporting arm 13 is extended vertically up from this plate 12, being secured thereto by screws 14. Tapered wedge lugs 15 are formed integrally with or 45 separately mounted upon the outer sides of the arms 1 for a purpose which will presently appear. Transversely aligned holes 16 are formed through the lower lugs 8, through which is journaled an operating shaft 17. A pair of lock arms 18 are 50 keyed at 19 upon the ends of the shaft 17 and adapted to play over the outer sides of the arms 1 and slidably engage the wedge lugs 15 as the shaft 17 is rotated.

A wedge shaped spreading lug or cam 20 is 55 likewise keyed at 21 centrally upon the shaft 17 between the two arms 1, the said lug 20 being extended oppositely to the arms 18. The outer extended end of the shaft 17 is squared as shown at 40 for engaging a crank handle 22 60

having a complementary squared socket 23 formed in one end for that purpose. The arrangement of the described parts is such, that as the handle 22 is rotated for example in a clockwise direction, 5 the arms 18 slidably engage the wedge lugs 15, whereby the arms 1 are forced towards one another, the spreading lug 20 being simultaneously turned outwardly away from the said arms. Upon the reverse rotation of the handle 22, however, the arms 18 are moved off of the lugs 15, 10 leaving the arms 1 free to spread laterally, while the spreading lug 20 simultaneously moves up between the lower ends of the arms 1, that is to say, between the lugs 8 and 9 of the two arms, 15 thus forcing the arms 1 asunder. The spreading lug 20 is tapered upon its entering side, as shown at 24, for facilitating this purpose.

In the use of the device thus embodied and described, a plurality of the same are seated 20 atop the shore posts already properly erected upon the lower floor 28 in manner above referred to, and the floor beams 25 are laid down edgewise upon the rests 12 and between the arms 1 and 13, after which the arms 1 are drawn 25 tightly up against the posts 2 through manipulation of the handles 22. Thus the several assemblies are locked firmly in position. It will be noted that the elements are so proportioned and arranged, that when the devices are mounted 30 atop the posts and the beams 25 are positioned therein, that there is left a substantial space 26 between the tops of the posts and the upper edges of the beams; this space provides a clearance between the upper flanges 3 of the 35 arms 1 and the flooring or sheeting 27 overhead.

In the modification shown in Figures 5 and 6, two sets of arms 1a and 1b are crossed angularly and mortised and jointed smoothly together at the crossing 30. Top flanges 3a are extended inwardly from the upper ends of the arms 1a and the side flanges 5b from the ends of the cross arms 1b. The plate 12a is pivotally anchored by means of pins 31 between the lower angularly protruding ends of the arms 1b. The arm 13a 40 is provided and attached to this plate as in the structure of Figures 1 to 4. The upper ends of the arms 1b are also extended beyond the face of the post 2 and are connected by a shaft 32 upon which is journaled a cam lever 33 provided 45 with a cam 34 at its working end. Thus by drawing the lever 33 downward, the arm 13a is drawn tightly up against the beam 25.

The structure shown in Figures 7 and 8 varies from that of Figures 5 and 6 in that the arm 55 13c is widened and extended down, blocks 36 being fastened to the sides of this arm to fill out the space even with the sides of the post 2, the arms 1c are slotted at their lower ends for adjustment purposes, as shown at 37, and are secured in place by means of a long bolt 31c extended through the assembly, as shown. The cam lever 33c and parts, are substantially similar to the lever 33 and parts, and is similarly mounted.

The invention as herein shown and described is 60 represented as formed for use upon a four-sided post, but the device may be readily modified for use upon round posts, if desired.

While we have herein described a certain 65 specific manner and method of constructing and 70 assembling the elements of our invention, it is understood that we may vary from the same in minor details, not departing from the spirit of our invention, so as best to construct a practical de-

vice for the purpose intended, as defined in the appended claims.

We claim:

1. In a device of the kind described, a pair of arms for positioning angularly across two opposite sides of the upper end of a post, the upper ends of the arms having inturned lugs for engaging the top of the post, the lower ends of the arms being adapted to protrude laterally of the intermediate face of the post and having inturned lugs thereat for engaging the post and also for jointly forming a stirrup, a beam rest removably mounted in the said stirrup, and means for tightening the assembly to the post. 10

2. In a device of the kind described, a pair of arms for positioning oppositely at the upper end of a post, the upper ends of the arms having inturned lugs for engaging the top of the post, the lower ends of the arms being adapted to protrude laterally of the intermediate face of the 20 post and being formed thereat to jointly constitute a socket, a beam rest mounted in the said socket, and a beam supporting arm extended from the beam rest. 25

3. In a device of the kind described, a pair of arms for positioning oppositely at the upper end of a post, the upper ends of the arms having inturned lugs for engaging the top of the post, the lower ends of the arms being adapted to protrude laterally of the intermediate face of the post and being formed thereat to jointly constitute a socket, a beam rest mounted in the said socket, a beam supporting arm extended from the beam rest, and means for tightening the elements to the post. 35

4. In a device of the kind described, the combination of a pair of hanger arms for positioning in a substantially vertical manner at opposite sides of the upper end of a post, with the lower ends of the arms adapted to protrude beyond the 40 face of the intermediate side of the post and being formed thereat to jointly provide a socket, the said lower socket forming ends having also transversely aligned shaft holes formed therethrough, a shaft journaled through the said shaft holes, 45 lock arms rigidly mounted at the outer ends of the shaft and adapted upon rotation of the shaft to move across the outer sides of the said hanger arms, means coacting with the movement of the lock arms over the hanger arms, whereby the latter are caused to close upon the post, and means for rotating the said shaft. 50

5. In a device of the kind described, a pair of hanger arms for positioning in a substantially vertical manner at opposite sides of the upper end 55 of a post, the lower ends of the arms being formed to jointly provide a socket supported laterally of the post, the said lower ends having also transversely aligned shaft holes, a shaft journaled through the said shaft holes, a spread cam rigidly 60 mounted upon the shaft between the hanger arms, lock arms rigidly mounted at the outer ends of the shaft for rotation with the shaft over the outer faces of the hanger arms, means coacting with the rotation of the said shaft and the resultant movement of the lock arms in one direction for pressing the hanger arms towards one another, the said spread cam functioning to press the said hanger arms asunder upon the reverse rotation of the shaft. 65
